CLAIM

The ornamental design for a frying and baking device, as shown and described.

DESCRIPTION

FIG. 1 is a first perspective view of a frying and baking device showing our new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a third perspective view showing the frying and baking device in an open state.

The broken lines in the drawings depict portions of the frying and baking device that form no part of the claimed design.
